UNITED STATES PATENT OFFICE.

MEAD HEDGLON, OF SYRACUSE, NEW YORK.

PORTABLE IRONING MACHINE.

Application filed November 3, 1926. Serial No. 146,044.

This invention relates to improvements in ironing machines of the type commonly used in the homes, and has for its object to provide a novel and simple machine, which is of light weight and readily portable by the operator, and is preferably driven and heated by electricity.

A further object is to provide a novel construction of the ironing shoe, which is preferably disposed horizontally, and is formed with an upwardly facing shallow longitudinal trough, in which a padded ironing roll rotates and produces the friction necessary to effect the ironing and smoothing of the articles as they are moved over a heated surface of the shoe. The ironing roll constitutes the driven member of the machine, and is rotatable in a fixed horizontal plane, by an electric motor. The shoe is disposed directly beneath, and its trough is normally arranged substantially concentric, to the roll. A further object is to provide a simple means for adjustably supporting the shoe, whereby the latter may be readily and quickly moved into and out of contact with the padded roll, whether or not the said roll is in motion. The forward side of the shoe is movable independently towards and away from the roll within a certain range, the said movement being controlled by an eccentric mechanism and suitable cushion means, in order to enable the operator to apply and adjust the articles. The tension means normally sustains the greater portion of the weight of the shoe, and may be adjusted for varying the ironing pressure. A particular object is to provide toggle means for pivotally supporting the rear portion of the shoe and for enabling the shoe to be moved bodily automatically in the direction and also in the counter direction of the travel of the articles, as well as to twist or rotate in a horizontal plane relatively to the axis of the roll, when inequalities in the thickness of the articles require such movements. The said toggle means cooperate with the eccentric mechanisms for enabling the shoe to gravitate from the roll with a rearwardly tilting motion for facilitating the recovering and adjusting of partially ironed and distorted articles. The shoe's pivotal supports are so disposed and coordinated that any inequalities of the ironing roll itself, as well as any variations in the thickness of the articles to be ironed, are taken care of in a manner to produce the

highest perfection effected by power machines. A further object is to provide means for preserving the flat and smooth condition of the ironed articles after they have passed beyond the ironing and pressing zone. And a further object is to generally improve and simplify the construction and operation of ironing machines of the class shown in my United States Patent No. 1,560,990, dated November 10, 1925.

I attain these objects by the means set forth in the detailed description which follows, and as illustrated by the accompanying drawings, in which—

Figure 1 is a top plan view of the complete machine. Fig. 2 is a front side elevation of the same, showing the toggle-links and the other parts in the ironing position. Fig. 3 is a rear end elevation of the machine, the parts being shown in the ironing position. Fig. 4 is a front end elevation of the same. Fig. 5 is a diagrammatic view showing the shoe and roll separated for inserting, or adjusting the articles prior to, as well as during the ironing. And Fig. 6 is an enlarged detail view of the clutch that controls the ironing roll.

In the drawings, 2 represents a wooden or other base on which the combined ironing and driving mechanisms are rigidly mounted and rendered easily portable as one part. The ironing roll preferably consists of a heavily padded cylinder 3, which may be rotated by a motor 4, the said roll being mounted in a fixed horizontal plane, by means of an upright gear-casing 5, and a goose-neck bracket 6. The roll 3 is provided at its opposite ends with short aligning shaft sections 3'-3^a that constitute the axis of the roll, the said sections being rigid with the roll. The casing 5 incloses the usual reduction gears, by which the power of the motor is transmitted to the roll 3. The gear-train comprises a worm 8, which is driven by the motor by means of a clutch 8'. The worm 8 meshes and drives a relatively large gear 9, which is mounted on a shaft 9'. The shaft 9' supports a pinion 9^a, which drives a larger spur gear 10, the latter gear being disposed concentric to the axis of the roll 3. The gear 10 is preferably loosely mounted on the shaft 3', upon which it may idle when the roll is stationary. The gear 10 is driven constantly by the motor, and the roll 3 is driven during the ironing operations by a clutch 12, which comprises the outer hub 10'

of the gear 10, and the corresponding end of an aligning sleeve 13 which is keyed to, and is slideable on shaft 3'. The sleeve 13 is provided with a circumferential groove 13', which is engaged by a pin 14, that projects from the lower end of a shaft 14', the said pin being disposed eccentric to the axis of said shaft, the said shaft extending upwardly through the top of the casing 5, and being fitted with a handle 15, by which the clutch is operated. The full and dotted lines in Figs. 1, 2, 3 and 4 show respectively the driving and the released position of the clutch operating handle.

7 15 7 represents the concave ironing shoe, whose length is substantially equal to that of the roll 3. The shoe 7 is disposed beneath and normally projects beyond the front side of the roll. The trough 7' of the shoe is normally disposed concentric to the roll 3. The shoe is hollow and its interior is fitted with electrical heating elements, as 7^a, of any suitable construction. The rear side of the shoe preferably normally terminates beneath 20 the roll, as shown in Figs. 1 and 3, instead of projecting beyond the roll, as shown in my former patent. The rear side of the shoe 7 is supported solely by similar links 7^c, the said members being located near the opposite ends of the shoe, as best seen in Figs. 2, 3 and 5. The top ends of the links 7^c are pivoted between lugs 7^b, which depend from the rear edge of the shoe, and the bottom ends of said members are similarly pivoted between lugs 5' and 6', that may be integral to the frame members 5 and 6. The connections between the opposite ends of the links 7^c and the several lugs are preferably somewhat loose in order to allow the ends of 25 the shoe to move horizontally in a twisting motion, independently of each other during the ironing, when hems, tucks, or similar inequalities in the thickness of the articles require such movements. The forward edge 30 of the shoe comprises a narrow lip 7^d, which projects beyond the roll 5 and cooperates with a detachable part 16, for forming a relatively broad table upon which the operator may spread the articles prior to feeding them 35 between the roll and the shoe. The table 16 is preferably spaced from the lip 7^d, in order to prevent the table from becoming too hot. A shaft 17 passes lengthwise beneath the lip 7^d, its opposite ends being journaled in and 40 projecting beyond end portions 7^e of the shoe, and upon the said ends are mounted respectively, a crank 18, which is fitted with an operating lever 18', and a crank 19, as shown. The cranks 18 and 19 are formed 45 with similar perforated lobes 18^a—19', which are engaged by the upper hook-ends of guide rods 20—20', the said rods extending downwardly from the lobes and passing loosely through perforated extensions 5^a—6^a of the frame members. The rods 20 are similarly

threaded intermediate their ends, to receive adjusting nuts 21—21', and between the nuts and the said extensions are disposed similar coil compression springs 22 through which the rods pass. The springs 22 when compressed by the downward swinging of lever 18' (see full lines in Figs. 1, 2, 3 and 4) tend to lift and hold the shoe 7 resiliently in the ironing position. The springs 22 yield forwardly and backwardly as well as upwardly and downwardly corresponding to the floating and twisting movements of the shoe during the ironing operations. Fig. 5 shows the position of the lever 18' when the shoe is lowered away from the roll by gravity. The perforations in the lobes 18^a and 19' are so disposed that when the lever 18' is swung downwardly, as shown in Figs. 1, 2, 3 and 4, the top ends of the rods 20—20' move inwardly past the axis of shaft 17 and prevent the accidental releasing and lowering of the shoe, until the operator swings the lever 18' upwardly, as shown in Fig. 5. The nuts 21—21' are employed for regulating the tension of the springs 22 for suitably supporting the relatively heavy shoe, and also for varying the ironing pressure of the shoe against the underside of the roll 3. The raising of the lever 18' also lifts the rods 20—20' and relieves the compression of the springs 22. This allows the shoe to gravitate away from the roll sufficiently to enable the operator to recover or adjust the articles in case they become distorted during the progress of the ironing. The shoe 7 may also be lowered for adjusting the articles in advance of the ironing. When the shoe 7 gravitates, as described, the link members 7^c effect the tilting or lowering of the rear side of the shoe to a greater extent than the forward side (see Fig. 5). This is very desirable, because the relatively broad gap at the rear of the machine and the inclination of the shoe greatly facilitates the ready recovery of articles that have been partially ironed without danger of straining, tearing or otherwise injuring the fabric. While the shoe is in the lowered position, shown in Fig. 5, the springs 22 still sustain their share of the weight of the shoe, and they are so arranged that they tend to limit the gravitational travel of the shoe. The crank 18 is provided with a rearwardly facing lug 18^b which is arranged to engage a stud 7^x carried by the shoe for arresting the releasing movement of the lever, as best seen in Fig. 4. The crank 19 is also arranged to engage a similar stop 19^a carried by the opposite end of the shoe, as shown in Fig. 3. The electric current for the motor 4, as well as for the heating elements 7^a, may be controlled by any suitable switch, as 23 (see Figs. 1, 2 and 4), wherein is shown two switch levers 23' and 23^a, which are set in the "on" position, and which respectively control the driving and the heat-

ing of the ironing parts. The arrows in Figs. 3, 4 and 5 indicate the direction of rotation of the roll 3. The forward edge of the shoe comprising the lip 7^a preferably 5 flares gradually away from the roll 3, for facilitating the entry and feeding of the articles during the ironing. The rear edge or terminus of the trough 7' of the shoe is relatively sharp, as shown at x, and the rear 10 face x' of the shoe below the said edge, is preferably arranged substantially at right angles to the plane of the ironing surface. This construction, when taken with the narrowing of the shoe, enables the articles as 15 they emerge from the pressing and ironing zone, to instantly gravitate towards the base 2 instead of being required to travel upwardly and rearwardly and to push the previously ironed portions over a curved lip 20 or margin similar to the lip 7^a, before starting the descent towards the receiving table, as shown in my former patent. This narrowing of the shoe not only shortens the travel of the ironed articles toward the receiving 25 table, but obviates all danger of the ironed portions of articles being wrinkled and distorted while being pushed or crowded over a relatively broad rear margin of the shoe, as explained. By narrowing the shoe, as 30 herein shown, the smooth condition of the ironed articles is preserved until the articles are finally laid away. This crimping and distorting of the ironed articles by the machine of my former patent frequently necessitates reironing of the more delicate and 35 light weight fabrics. This trouble and annoyance is entirely obviated by the arrangement of the present machine, which is capable of handling articles, that are extremely light 40 and thin, and at the same time perform satisfactory ironing of articles that are relatively heavy and thick. In either case by narrowing the shoe and providing the relatively sharp edge x, and the abrupt surface x' of 45 the shoe below said edge, as herein shown, enables me to effect the smoothing and ironing of light as well as heavy fabrics by a single operation, without requiring re-ironing of any of the articles, and without necessitating any change, except a slight re-adjustment of the tension of the ironing mechanism.

In Figs. 2, 3, 4 and 5, the links 7^c are 50 shown formed with extensions 7^c, which are connected by tension springs 2' with lugs 2^a, the springs 2' exert a constant pull on the extensions 7^c and tend to swing the links rearwardly, as shown in Fig. 5, whenever 55 the tension of the springs 22 is relaxed for lowering the shoe. The springs 2' effect the positive disengagement of the margin x of the shoe, (see Fig. 5), which without the 60 said springs tends to retain its contact with the roll 3 when the shoe is released. The 65 power of the springs 2' is but a fraction of

that of the springs 22, and the weaker springs are readily overcome by the stronger springs, when the hand-lever 18' is swung downwardly for effecting the ironing pressure of the shoe against the roll.

Having thus described my invention, what I claim, is—

1. In a portable ironing machine, the combination with a driven padded roll supported by spaced frame sections, of a heated trough-like shoe normally disposed horizontally beneath said roll, a pair of links for supporting the rear side of the shoe, said links being loosely pivoted to the shoe and to said frame sections for enabling the shoe to twist in a horizontal plane, compression springs resiliently supporting the forward side of the shoe adapted to control the pressure of the shoe against the underside of the roll, and eccentric means for swinging the shoe downwardly and rearwardly, and for locking the shoe in the ironing position.

2. In a portable ironing machine, the combination with a driven padded roll supported by spaced frame sections, of a heated trough-like shoe disposed horizontally beneath said roll, the forward side of said shoe projecting beyond the roll, the rear side of said shoe terminating beneath the roll, a pair of links supporting the rear side of the shoe, and compression springs resiliently supporting the forward side of the shoe adapted to effect variable ironing pressure of the shoe against the underside of the roll.

3. In a portable ironing machine, the combination with a driven press roll supported by spaced frame sections and a receiving table below said roll, of a heated concave shoe disposed horizontally beneath the roll, the forward side of the shoe being normally disposed in a higher plane than the bottom of the roll, the rear side of the shoe being disposed substantially in the same plane as the bottom of the roll and being formed with a relatively sharp edge that enables the ironed articles to effect a sheer descent towards the receiving table, means for resiliently supporting the shoe and for varying the pressure of the shoe against the roll, and means for lowering the shoe for adjusting and recovering articles that are partially ironed.

4. In a portable ironing machine, the combination with a driven padded roll supported by spaced frame sections, of a heated shoe having an upwardly facing concave in which the roll rotates, the forward side of the shoe being formed with a flared lip that projects beyond the roll, the rear side of the shoe being formed with a relatively sharp corner that is disposed beneath the roll, links supporting the rear side of the shoe, the bottom ends of said links being pivoted to the frame sections, their top ends adapted to swing forwardly and backwardly when

the shoe is raised and lowered relatively to the roll, tension means for resiliently supporting the forward side of the shoe in the ironing as well as in the released position, and eccentric mechanisms for raising and lowering the shoe and for locking the shoe in the ironing position.

5. In a portable ironing machine, the combination with a driven press roll supported by spaced frame sections and a receiving table disposed below the roll, of a heated concave shoe disposed horizontally beneath the roll, the forward side of the shoe being disposed normally in a higher plane than the bottom surface of the roll, the rear side of said shoe being disposed substantially in the plane of said bottom surface and terminating in a relatively sharp edge that enables the ironed articles to effect a sheer descent towards the receiving table for preventing crimping and distorting of the articles, links for supporting the rear side of said shoe, said links adapted to swing in planes at right angles to the axis of the roll during the lowering and raising of the shoe, tension means for resiliently supporting the forward side of the shoe in the ironing as well as in the released position, and eccentric mechanisms adapted to control the swinging of said links.

6. In a portable ironing machine, the combination with a driven padded ironing roll, of a concave shoe disposed beneath said roll, the concave surface of the shoe conforming to the curvature of the roll and adapted to be heated during the ironing operations, the forward side of the shoe comprising a flaring lip that projects beyond the roll, an eccentric mechanism for controlling the raising and lowering of the shoe, springs for resiliently supporting the forward side of the shoe, said springs being operatively connected with said eccentric mechanism, link means for supporting the rear side of the shoe adapted to cooperate with the eccentric mechanism for effecting the lowering of the shoe at an inclination to the normal ironing position of the shoe, the rear side being formed with a relatively sharp edge over which the ironed articles travel, and from which the said articles gravitate in a path perpendicular to the plane of the ironing position of the shoe.

7. In a portable ironing machine, the combination with a driven roll supported by spaced frame sections and a receiving table disposed below the roll, of a heated concave shoe normally disposed horizontally beneath the roll, the forward side of the shoe projecting beyond the roll, the rear side of the shoe terminating beneath the roll and being formed with a relatively sharp edge over which the ironed articles travel immediately they emerge from the ironing zone and from which the articles effect a sheer descent to-

wards the receiving table, links pivoted to and supporting the rear side of the shoe adapted to swing the said side downwardly for facilitating the recovery and adjustment of partially ironed articles, and tension means supporting the forward side of the shoe adapted to provide variable ironing pressure as well as to resiliently support the said side in the ironing and released positions.

8. In a portable ironing machine, the combination with a driven padded ironing roll, of a heated concave shoe disposed beneath said roll, the concave surface of the shoe adapted to be heated during the ironing operations, the forward side of the shoe comprising a flaring lip that projects beyond the roll, a shaft extending longitudinally beneath said lip, an eccentric mechanism mounted on said shaft for controlling the raising and lowering of the shoe, springs for resiliently supporting the forward side of the shoe, said springs being operatively connected with said eccentric mechanism, link means for supporting the rear side of the shoe adapted to incline the shoe when the latter is lowered by the eccentric mechanism, the rear side of the shoe terminating beneath the roll and being formed with a relatively sharp edge over which the ironed articles travel, and from which the said articles gravitate in a path perpendicular to the plane of the said roll.

9. In a portable ironing machine, a concave heated shoe, a driven press roll disposed in the concave of the shoe, eccentric mechanisms for moving the shoe towards and away from the roll, springs for resiliently supporting the shoe adapted to be compressed by the eccentric mechanisms for effecting the ironing pressure, means for adjusting said springs for varying the ironing pressure, the forward side of said shoe projecting beyond the roll for facilitating feeding the unironed articles between the roll and the shoe, the rear side of said shoe being disposed beneath the roll for facilitating the sheer descent of the ironed articles as they emerge from the ironing zone, and a pair of links supporting the rear side of the shoe and cooperating with the springs for effecting the ironing pressure.

10. In a portable ironing machine, the combination with a driven padded press roll and a receiving table disposed below the roll, of a heated concave shoe disposed horizontally beneath the roll during the ironing operations, the rear side of the shoe terminating beneath the roll, and being formed with a relatively sharp edge extending the length of the roll for enabling the ironed articles to effect a sheer drop towards the receiving table for preventing crimping and distorting of the articles after they emerge from the ironing zone, means for moving the shoe towards and away from the roll,

and link members for supporting the rear side of the shoe, said members being loosely pivoted for enabling the shoe to twist in a horizontal plane relatively to the roll.

- 5 11. In a portable ironing machine, the combination with a driven press roll supported by spaced frame sections, of a heated trough-like shoe disposed horizontally beneath the roll, tension means for pressing 10 the forward side of the shoe against the roll during the ironing operation, links pivoted to the frame sections adapted to press and hold the rear side of the shoe against the roll, springs for swinging said links rearwardly for lowering the rear side of the shoe, and eccentric means carried by the forward side of the shoe adapted to cooperate with the links for raising and lowering the shoe.

- 20 12. In a portable ironing machine, the

combination with a base and a driven padded ironing roll supported by frame sections parallel to the base, of a heated trough-like shoe disposed beneath said roll adapted to be lowered for the recovery and adjustment of articles being ironed, links pivoted to the frame sections and to the rear margin of the shoe adapted to effect the raising and lowering of said margin, resilient means for supporting the forward side of the shoe and for varying the ironing pressure, springs for swinging the links away from the roll when the tension at the forward side of the shoe is relaxed, and eccentric means for controlling the lowering and raising of the shoe 35 and for locking the shoe in the raised position.

In testimony whereof I affix my signature.

MEAD HEDGLON.
